WINDOW SHADE ATTACHING MEANS

Fred J. Burns, Saginaw, Mich., assignor to The Columbia Mills, Inc., New York, N. Y.

Application July 27, 1944, Serial No. 546,813

2 Claims. (Cl. 160—390)

This invention relates to means for fastening a conventional window shade to a shade roller, and is particularly concerned with means mounted on the roller and detachably engaging the shade so that a worn or mutilated shade can be quickly removed and a new shade easily and accurately attached by the housewife.

In a collateral way, the invention is likewise concerned with attaching a reversible shade to a roller. In this type of construction, the positioning of the shade on the roller may be reversed after the exposed portion of the shade has been soiled or worn.

One of the prime objects of the invention is to provide simple, practical and inexpensive attaching means which can be readily mounted on the roller, and by means of which a shade can be attached or removed, and a new shade substituted by the housewife without in any manner marring, tearing or otherwise disfiguring the shade in the vicinity of the point or points of attachment.

Another object is to provide a shade attaching means of very simple construction which can be easily and inexpensively manufactured and mounted in attaching position on the roller with great facility.

A further object is to provide an attaching means to which a shade may be quickly, accurately and easily attached and/or detached, which requires no tools to manipulate, and which when the shade is in position, lies flat against the roller body so that there is no interference with the winding operation, nor is there any difference in the appearance of the shade when wound.

The foregoing and other objects are attained by the means described herein and broadly disclosed in the accompanying drawing.

In the drawing:

Fig. 1 is a fragmentary, elevational view of a shade roller and shade showing my shade attaching clasps secured thereon.

Fig. 2 is an enlarged view showing the blank from which the clasp is formed.

Fig. 3 is a side, elevational view showing the clasp formed to shape.

Fig. 4 is an end view of the formed clasp.

Fig. 5 is a view similar to Fig. 2 illustrating a slightly modified construction.

Fig. 6 is a side, elevational view of the formed clasp.

Fig. 7 is an end view thereof.

Fig. 8 is a side, elevational view similar to Fig. 55

3, showing the clasp formed with but two anchoring prongs.

Fig. 9 is an end view thereof.

Fig. 10 is a view similar to Fig. 8 showing an alternate construction.

Fig. 11 is an end view thereof.

Fig. 12 is an enlarged, transverse, sectional view through the roller and shade.

Fig. 13 is a fragmentary view of the bottom end of the shade illustrating the perforations.

Referring now to the drawing in which I have shown the preferred embodiments of my invention, the numeral 15 indicates a shade roller such as is at present in general use, a window shade 16 being attached thereto and is windable thereon, and this shade can be formed of any desired material.

The present invention is directed to a shade attaching means or clasp so designed that it can be readily mounted in position, and by means of which a shade may be permanently secured to a roller, or by means of which the shade may be detachably secured in position.

The shade attaching means is mounted on 25 and secured to the roller 15 and can be either a stamping formed of relatively thin, readily bendable material with prongs formed integral therewith, or it can be a stamping having tacks assembled thereon, the principle, mounting, and 30 operation being exactly the same.

Referring now more specifically to Figs. 2, 3, 4, 6 and 9 of the drawing in which I have shown prongs formed integral with the clasp. The numeral 17 indicates a stamped blank, shaped as 35 clearly shown in Fig. 2 of the drawing, the end sections 18 forming wings, bent on the line 19 and foldable over and onto the main body, thence the ends are again bent on the line 20, at right angles to the body, so that the wing extends 40 vertically as clearly shown in Figs. 3 and 4.

Relatively sharp prong sections 21 are formed integral with and project from the edges of the body of the stamping, these prongs being bent on the bending line 22 so that they project downwardly as shown in Fig. 3, so that they readily pierce the body of the roller 15, and firmly anchor the clasp in position. These clasps are mounted in longitudinally, spaced apart, relation on the roller as shown, the spacing from the one side edge of the roller being uniform at all times.

Openings 23 are provided in the shade material 16 at a point directly adjacent the one end thereof, the opening 24 being spaced a predetermined distance from the one side edge of the material, the spacing of the intermediate open-

ings being standardized so that any suitably perforated shade can be applied to any roller.

In mounting the shade, the openings 23 are brought into register with the vertical wings 18 of the spaced clasp members, these wings project through the openings and are then bent down as indicated in Fig. 1 so that they lie flat and snug against the roller, thus securely anchoring the shade in position.

In the construction above described, I have shown the clasp formed with four individual prongs, and in Figs. 8 and 9 the clasp has but two prongs, this two-prong construction requires slightly less material, but the principle of attachment and operation is exactly the same.

In Figs. 5, 6, 7, 10 and 11 I have shown a slightly modified construction in which the prongs 21 are omitted, openings 25 being punched in the blank 17, and these openings accommodate small tacks 26 which are inserted therein, the openings being of smaller diameter than the heads of the tacks, and when the base of the wing sections 18 are folded down on the main body of the stamping, the heads of the tacks will be confined between the face of the stamping 17 and the face of the wing section 18, thus firmly securing the tacks in position, this modified construction is applied in exactly the same manner as is the construction first described, Figs. 6 and 7 showing a two-tack design, while Figs. 10 and 11 show but a single tack arrangement for anchoring.

If it is desired to permanently attach the shade to the roller, the shade is first placed in position and the clasps utilized as tacks, the wings lying flat against the roller, and the shade can of course be cut or torn free when desired, so that a replacement can be added and secured by the wings, this makes a very satisfactory arrangement as the strain on the clasp is limited due to the material being wound on the roller.

To facilitate the attachment of reversible shades, I provide openings 27 in the lower hem of the shade in which the stiffening slat 28 is mounted, these openings face the outside when the shade is hung, so they are not visible from the interior, and when it is desired to reverse the shade, the thread 29 forming the lower hem is removed, the shade is then reversed end for

end and the perforations 23 and 24 will register with the clasps, the hem is then provided in the previously attached end and the shade is ready for use.

5 This attaching means insures accurate parallel anchorage of the shade, it will wind up evenly, and it further permits the shades to be adjusted to uniform length in multiple windows.

The herein described construction and arrangement admits of considerable modification without departing from the invention; I therefore do not wish to be limited to the precise arrangements shown and described, which is broadly for the purpose of illustration, as the scope of protection is to be taken solely from the appended claims, interpreted as broadly as is consistent with the prior art.

What I claim is:

1. The combination with a shade roller, of a fastener permanently anchored to the roller for detachably attaching a shade provided with spaced-apart perforations therein, said fastener comprising a body portion formed of relatively thin material with relatively sharp depending means embedded in the roller for anchoring the fastener in said roller, and vertically disposable bendable wings formed integral with the fastener bendable over the body portion with the end sections bent upwardly and projectable through one of said perforations and bendable over the shade adjacent the perforation to secure the shade on the roller.

2. The combination with a shade roller of a fastener permanently anchored to the roller for detachably securing a shade provided with a plurality of perforations along an end thereof, said fastener comprising a relatively thin sheet metal stamping provided with relatively sharp depending prong members formed integral therewith and embedded in the roller for anchoring the fastener in position, elongated wings formed integral with the main body and foldable over and onto the main body of the stamping, with the end sections of the wings bent upwardly for passage through one of said perforations, said end sections being bendable to and from position to secure the shade over said fastener body.

FRED J. BURNS.
